UNITED STATES PATENT OFFICE

161,940

MOTION-PICTURE CAMERA

Frederick G. Knowles, Rochester, N. Y., assignor
to Eastman Kodak Company, Rochester, N. Y.,
a corporation of New Jersey

Application August 5, 1950, Serial No. 11,618

Term of patent 14 years

(Cl. D61—1)

To all whom it may concern:

Be it known that I, Frederick G. Knowles, a citizen of the United States, residing in Rochester, in the county of Monroe and State of New York, have invented a new, original and ornamental Design for a Motion Picture Camera, of which the following is a specification, reference being had to the drawings, forming a part thereof, in which:

Fig. 1 is a perspective view of a motion picture camera showing my new design, this view showing one side and parts of the front and top;

Fig. 2 is a bottom plan view of the motion picture camera shown in Fig. 1;

Fig. 3 is a perspective view of the camera shown in the preceding figures showing the opposite side of the camera from that shown in Fig. 1, the back, and parts of the top of the camera.

I claim:

The ornamental design for a motion picture camera as shown.

FREDERICK G. KNOWLES.
